CLAIM

The ornamental design for a touch screen, as shown and described.

DESCRIPTION

FIG. 1 is a front perspective view of a touch screen according to the present disclosure;

FIG. 2 is a rear perspective view of the touch screen of FIG. 1;

FIG. 3 is a front view of the touch screen of FIG. 1;

FIG. 4 is a rear view of the touch screen of FIG. 1;

FIG. 5 is a top view of the touch screen of FIG. 1;

FIG. 6 is a bottom view of the touch screen of FIG. 1;

FIG. 7 is a right side view of the touch screen of FIG. 1;

FIG. 8 is a left side view of the touch screen of FIG. 1;

FIG. 9 is an enlarged view of a portion of FIG. 2; and,

FIG. 10 is an enlarged cross-sectional view of the touch screen taken in the direction of line 10-10 in FIG. 8.

The broken lines shown in the drawings depict portions of the touch screen that form no part of the claimed design.
